TELEPHONE-EXCHANGE SYSTEM.

1,297,358.

Specification of Letters Patent.

Patented Mar. 18, 1919.

Application filed January 2, 1918. Serial No. 209,972.

To all whom it may concern:

Be it known that I, CHARLES W. KECKLER, a citizen of the United States, residing at Newark, in the county of Essex, State of New Jersey, have invented certain new and useful Improvements in Telephone-Exchange Systems, of which the following is a full, clear, concise, and exact description.

This invention relates to telephone systems and more particularly to such systems in which telephone lines of different characters terminating at a central office may be interconnected indiscriminately by means of a universal link circuit.

The object of this invention is to provide a simple and inexpensive system of this character by means of which the work of the operator is simplified and the time required for completing connections between the subscribers' lines is reduced.

In accordance with one feature of this invention, there is provided in a usual link or connecting circuit, a listening relay which automatically connects an operator's telephone set with a calling line upon the connection of the link circuit therewith and which automatically disconnects such operator's telephone set when the link circuit is connected with the called line, irrespective of the character of the calling or called lines.

This and other features not specifically mentioned above, may be fully understood from the following specification and the annexed drawing, in which is illustrated one embodiment of this invention.

In the accompanying drawing there is shown an ordinary common battery subscriber's line A and a local battery subscriber's line B terminating at a central office at which there is provided a universal cord circuit C for interconnecting the subscribers' lines. For the sake of simplicity, only two such lines are shown, although it will be understood that a plurality of each of such classes of lines may terminate at the central office. The universal cord circuit C may be used indiscriminately to interconnect two local battery lines, two common battery lines or a local and a common battery line. All portions of the cord circuit C, unessential to the present invention, have been omitted.

The cord circuit C is provided with a differentially wound listening relay 4 having windings 5, 6 and 7, of which winding 5 is

placed in series with the marginal relay 3 in the sleeve conductor of the answering portion of the cord circuit and winding 7 is similarly associated with marginal relay 8 in the sleeve conductor of the calling portion of the cord circuit, while the auxiliary or compensating winding 6 is connected between the armatures of the relays 3 and 8. Relays 3 and 8 are both adapted to operate when connected in series with the comparatively low resistance sleeve conductors of the common battery lines and to remain unoperated when connected in series with the comparatively high resistance sleeve conductors of the local battery lines. Windings 5 and 7 are of the same resistance and number of turns, while winding 6 has one half as many turns as winding 5 or 7. Windings 5 and 7 are connected in opposition, while the effect of winding 6 depends upon the positions occupied by the armatures of relays 3 and 8.

It is thought that the invention will be more fully understood from the following description of the operation of the system.

If it is desired to interconnect two local battery lines, the answering plug 1 is inserted in the jack of the calling magneto line, thereby operating the listening relay 4 and the cut-off relay associated with such line, over a circuit proceeding from battery, through winding 5 of relay 4, winding of marginal relay 3, sleeves of plug 1 and of the jack of the calling line, winding of cut-off relay (similar to cut-off relay 10 of line B) to ground. However, marginal relay 3 does not operate, due to the high resistance sleeve of the calling line. Listening relay 4, in operating, associates the operator's telephone set with the link circuit and thereby places the operator in communication with the calling subscriber. Upon being advised that the calling subscriber desires to converse with the subscriber on local battery line B, the operator inserts calling plug 9 in the jack of line B, whereby a circuit is established from battery, through winding 7 of listening relay 4, winding of marginal relay 8, sleeves of plug 9 and of the jack of line B, winding of cut-off relay 10 to ground. As in the former case, cut-off relay 10 operates while marginal relay 8 will remain unoperated. Since the two connected lines have the same sleeve resistance, the resistance of the circuit just traced agrees with that of the similar

circuit previously traced in connection with the answering portion of the cord circuit. Therefore, since the windings 5 and 7 contain equal numbers of turns and are connected in opposition, relay 4 will release, disconnecting the operator's telephone set from the cord circuit.

- If two common battery lines are to be interconnected, the insertion of answering plug 1 in the jack of line A will complete a circuit extending from battery, through winding 5 of relay 4, winding of marginal relay 3, sleeves of plug 1 and of the jack of line A, winding of relay 2 to ground. Relays 2 and 4 operate as before and, due to the low resistance sleeve of line A, marginal relay 3 also operates, completing a circuit from battery, through alternate contact of relay 3, winding 6 of relay 4, normal contact of relay 8 to ground. Since the winding 6 has one half as many turns as winding 5 and is now connected in opposition thereto, the flux density in the core of relay 4 is reduced, due to the current flowing in winding 6. Ascertaining that a connection with another common battery line is desired, the operator inserts the calling plug 9 in the jack of a common battery line, and thereupon a circuit is established from battery, through winding 7 of relay 4, winding of marginal relay 8, sleeves of plug 9 and of the jack of the called common battery line, winding of the cut-off relay associated with such line (similar to relay 2 of line A) to ground. The cut-off relay of the called line thereupon operates and, due to the low resistance of the sleeve circuit of such line, marginal relay 8 also operates, rendering winding 6 of relay 4 ineffective. The resistances of the sleeve circuits including windings 5 and 7 being equal and such windings being connected in opposition, relay 4 releases, as in the former case, disconnecting the operator's telephone set from the cord circuit.
- In case a subscriber on a common battery line desires to converse with a subscriber on a local battery line, the calling plug 1, upon being inserted in the jack of line A, completes a circuit from battery, through winding 5 of relay 4, winding of relay 3, sleeves of plug 1 and of the jack of line A, winding of cut-off relay 2 to ground. As previously described, relays 2, 3 and 4 operate, connecting the operator's telephone set with the cord circuit and placing winding 6 of relay 4 in opposition to winding 5. Upon being advised that connection with line B is desired, the operator inserts calling plug 9 in the jack of line B, establishing a circuit from battery, through winding 7 of relay 4, winding of marginal relay 8, sleeves of plug 9 and of the jack of line B, winding of cut-off relay 10 to ground. Relay 10 operates, but due to the high resistance sleeve of line B, relay 8 does not operate, and the amount of current

flowing through winding 7 of relay 4 is less than that flowing through winding 5 which is connected in opposition thereto. However, the effect of the current flowing through the equalizing or balancing winding 6, which also opposes that of winding 5, is sufficient to completely overcome the effect of winding 5 and to cause the release of relay 4, disconnecting the operator's telephone set from the cord circuit.

In case a subscriber on a local battery line desires to converse with the subscriber on a common battery line, the operator inserts the answering plug 1 in the jack of the calling local battery line, completing thereby a circuit from battery, through winding 5 of relay 4, winding of relay 3, sleeves of plug 1 and of the jack of the calling line, winding of the cut-off relay (similar to relay 10 of line B) to ground. As previously described, listening relay 4 and the cut-off relay of the calling line operate, while marginal relay 3 does not operate. Upon being advised that a connection with a common battery line is desired, the operator inserts the calling plug 9 in the jack of the wanted common battery line, establishing thereby a circuit from battery, through winding 7 of relay 4, winding of relay 8, sleeves of plug 9 and of the jack of the called line, winding of the cut-off relay (similar to relay 2 of line A) to ground. As previously described, the cut-off relay and marginal relay 8 operate. In operating, relay 8 completes a circuit from battery, through alternate contact of relay 8, winding 6 of relay 4, normal contact of relay 3 to ground. Since the resistance of the called line is comparatively low, the current flowing through winding 7 is considerably in excess of that flowing through the opposing winding 5 which is connected to the line having a high resistance sleeve. However, in this case, the current flows through winding 6 in a different direction so that it produces an effect in opposition to that of the current in winding 7, and the combined effect produced by the currents in windings 6 and 7 exactly neutralizes the effect produced by the current in winding 5, and relay 4 is therefore released as before.

It will thus be seen that the auxiliary or compensating winding 6 of relay 4 assists in the release of such relay whenever lines of different characters are interconnected, while such winding is not employed in case the interconnected lines are similar in character. It is also evident that either end of the cord circuit may be used either for answering or for calling purposes.

What is claimed is:

1. A telephone exchange system comprising a plurality of common battery and local battery telephone lines, a link circuit for interconnecting the lines indiscriminately, an operator's telephone set, a differential relay

having a winding associated with each end of the link circuit and operating when one end thereof is connected with a calling line of either character to connect the telephone set therewith, a compensating winding for the relay, and means in each end of the link circuit for rendering the compensating winding effective while the link circuit interconnects the lines of different characters, thereby releasing the relay to disconnect the telephone set.

2. A telephone exchange system comprising a plurality of common battery and local battery telephone lines, a link circuit for interconnecting the lines indiscriminately, an operator's telephone set, a differential relay having a winding associated with each end of the link circuit and operating when one end thereof is connected with a calling line of either character to connect the telephone set therewith, a compensating winding for the relay, and a relay in each end of the link circuit for rendering the compensating winding effective while the link circuit interconnects the lines of different characters, thereby releasing the relay to disconnect the telephone set.

3. A telephone exchange system comprising a plurality of common battery and local battery telephone lines, a link circuit for interconnecting the lines indiscriminately, an operator's telephone set, a differential relay having a winding associated with each end of the link circuit and operating when either end thereof is connected with a calling line of either character to connect the telephone set therewith, a compensating winding for the relay, and means in each end of the link circuit for rendering the compensating winding effective while the link circuit interconnects the lines of different characters, thereby releasing the relay to disconnect the telephone set.

4. A telephone exchange system comprising a plurality of common battery and local battery telephone lines, a link circuit for interconnecting the lines indiscriminately, an operator's telephone set, a differential relay having a winding associated with each end of the link circuit and operating when either end thereof is connected with a calling line of either character to connect the telephone set therewith, a compensating winding for the relay, and a relay in each end of the link circuit for rendering the compensating winding effective while the link circuit interconnects the lines of different characters, thereby releasing the relay to disconnect the telephone set.

5. A telephone exchange system comprising a plurality of common battery and local battery telephone lines, a link circuit for interconnecting the lines indiscriminately, an operator's telephone set, a differential relay having a winding associated with each end

of the link circuit and operating when one end thereof is connected with a calling line of either character to connect the telephone set therewith, a third winding for the relay for compensating for difference in ampere turns of the other two windings, switching means in each end of the link circuit, and a circuit for the third winding including contacts of both switching means for rendering the third winding effective while the link circuit interconnects the lines of different characters, thereby releasing the relay to disconnect the operator's telephone set.

6. A telephone exchange system comprising a plurality of common battery and local battery telephone lines, a link circuit for interconnecting the lines indiscriminately, an operator's telephone set, a differential relay having a winding associated with each end of the link circuit and operating when one end thereof is connected with a calling line of either character to connect the telephone set therewith, a compensating winding for the relay, a circuit for the compensating winding, and a relay in each end of the link circuit jointly controlling the circuit of the compensating winding to render the associated winding effective while the link circuit interconnects the lines of different characters, thereby releasing the relay to disconnect the operator's telephone set.

7. A telephone exchange system comprising a plurality of common battery and local battery lines, a link circuit for interconnecting the lines indiscriminately, an operator's telephone set, a differential relay having a winding associated with each end of the link circuit and operating when one end thereof is connected with a calling line of either character to connect the telephone set therewith, a compensating winding for the relay for compensating for difference in ampere turns of the other two windings, and means in each end of the link circuit cooperating to determine the direction of current flow through the compensating winding, thereby releasing the relay to disconnect the operator's telephone set while the link circuit interconnects the lines of different characters.

8. A telephone exchange system comprising a plurality of common battery and local battery lines, a link circuit for interconnecting the lines indiscriminately, an operator's telephone set, a differential relay having a winding associated with each end of the link circuit and operating when one end thereof is connected with a calling line of either character to connect the telephone set therewith, a compensating winding for the relay for compensating for difference in ampere turns of the other two windings, and a relay in each end of the link circuit cooperating to determine the direction of current flow through the compensating wind-

- ing, thereby releasing the relay to disconnect the operator's telephone set while the link circuit interconnects the lines of different characters.
- 5 9. A telephone exchange system comprising a plurality of common battery and local battery telephone lines, a link circuit for interconnecting the lines indiscriminately, an operator's telephone set, a differential relay having a winding associated with each end of the link circuit and operating when one end thereof is connected with a calling line of either character to connect the telephone set therewith and releasing when the 10 link circuit interconnects lines of like character to disconnect the operator's telephone, a compensating winding for the relay adapted to aid either of the other windings in releasing the relay when the link circuit 15 interconnects the lines of different characters, and means in each end of the link circuit coöperating to determine the winding to be aided.
- 20 10. A telephone exchange system comprising a plurality of common battery and local battery telephone lines, a link circuit for interconnecting the lines indiscriminately, an operator's telephone set, a differential relay having a winding associated with each end of the link circuit and operating when one end thereof is connected with a calling line of either character to connect the telephone set therewith and releasing when the link circuit interconnects lines of like character to disconnect the operator's telephone, a compensating winding for the relay adapted to aid either of the other windings in releasing the relay when the link circuit 25 interconnects the lines of different characters, and a relay in each end of the link circuit coöperating to determine the winding to be aided.
- 30 15 35
- 40

In witness whereof, I hereunto subscribe my name this 28th day of December, A. D. 1917.

CHARLES W. KECKLER.
